METHOD OF MANUFACTURING SLIDERS FOR SLIDE FASTENERS

Frederick Ulrich, Jersey City, N. J., assignor to Conmar Products Corporation, Newark, N. J., a corporation of New Jersey

Application January 18, 1951, Serial No. 206,580

8 Claims. (Cl. 29—410)

The invention relates to slide fasteners and more particularly to the manufacture of sliders for slide fasteners.

In the patent to Richard Low, Number 2,372,837, granted April 3, 1945, having the same assignee as the present invention, it has been proposed to form a slider body blank by a rolling operation. There are many advantages to be realized in forming a slider body by rolling. However, the method disclosed by Low has several limitations. The rolls of Low are each formed with projections and recesses to form the side flanges, neck portion and lug for receiving the pull. Such rolls are of comparatively complicated contour, are expensive to make, and are not easily maintained over the long periods required for commercial runs.

Another limitation of the method of manufacture described in the Low patent is that it results in a slider of limited usage. The simplest form of the slider disclosed in the patent will not operate satisfactorily when the fastener is subjected to cross-pull during the closing movement of the slider. This may be overcome to some extent in the other slider constructions disclosed in the patent wherein long additional, laterally offset flanges are provided. A large amount of metal is required for fabrication of these sliders, without best satisfying the desired running qualities of the fastener. Aside from the added cost of additional material, such sliders are undesirable from the conservation standpoint in a period of critical metal shortages.

In accordance with my invention, a simplified rolling operation is used to form the flanges of slider bodies made from a strip of continuous length. The resulting slider possesses universal application. The slider is manufactured with the use of a minimum amount of material, and with scrap kept to an exceedingly small amount. Because of my simple method of manufacture, the dimensional accuracy of the product may be closely controlled, and the slider functions in a highly satisfactory manner under all conditions of usage.

To accomplish the foregoing general objects, and such other more particular objects as may hereinafter appear, my invention consists in the novel method steps for manufacturing sliders, and their relation one to another, as are hereinafter more particularly described in the specification, and sought to be defined in the claims. The specification is accompanied by a drawing in which:

Fig. 1 is an end elevation of a pair of rolls operating upon a continuous strip of material to form the slider walls and the side flanges;

Fig. 2 is a section, on an enlarged scale, taken approximately in the plane of line 2—2 of Fig. 1 illustrating the manner in which the strip of material is deformed by the rolls;

Fig. 3 is a section taken along the line 3—3 of Fig. 1, showing the original preferred form of the strip prior to its deformation by the rolls;

Fig. 4 is a section taken on the line 4—4 of Fig. 1, showing the strip after deformation by the rolls;

Fig. 5 is a partially sectioned, schematic perspective

2

view of means for forming a slider body from the rolled strip; and

Fig. 6 is a perspective view of a finished slider body resulting from my novel method of manufacture.

Referring to the drawings and more particularly to Figs. 1, 2 and 3, a continuous strip of wire 12, preferably of metal, is fed between a pair of pressure rolls 14 and 16. As shown in Fig. 3, the strip 12 is flat and of uniform rectangular cross-section. It is deformed by the pressure rolls 14 and 16 so that it assumes the shape shown in Fig. 4, where the strip, now designated 18, is provided with parallel, unbroken, projecting flanges 20 and 22 extending continuously along each longitudinal edge of the strip. The distance between the flanges 20 and 22 is equal to the desired width of the closing or stem end of the finished slider.

The mating of the rolls 14 and 16 and their coaction is shown in Fig. 2 of the drawing. The rolls are provided with mating portions 24 and 26 of such relative dimensions that the material of the strip is completely confined between the deforming portions of the rolls as the strip is being rolled into the cross-sectional shape of the flanged strip 18. It will be understood, of course, that the deformation of the strip 12 to the cross-sectional shape of the flanged strip 18 results in a reduction in the thickness of the original strip, such reduction in thickness serving to fully fill-in the continuous flanged portions 20 and 22. If desired, the rolling of the strip may be accomplished by passing the wire or strip through a pair of preliminary rolls to partially deform the strip before final deformation in a second set of rolls. Also, while the preferred form of the invention contemplates the formation of the flanged strip 18 by rolling, such a flanged strip may be formed by extrusion.

The continuously flanged strip 18 is then subjected to a series of forming operations, as shown in Fig. 5. The strip is acted upon progressively, and may, if desired, be worked upon in a so-called "single progressive die." As shown, the flanged strip 18 is acted upon by a flattening and flaring punch 28 (the die for supporting the strip 18 is not shown). The punch 28 serves to flatten the continuous, unbroken flanges 20 and 22 at predetermined, spaced intervals, and at the same time serves to outwardly flare the portions of the flanges adjacent the flattened areas. The flattened area is indicated at 30, and the outwardly flared portions of the flanges 20 and 22 are designated at 32, 32' and 34, 34', respectively. It will be apparent that the flattening and flaring operations may be accomplished separately. It is preferred, however, to accomplish these two operations simultaneously as shown.

To accomplish the flattening and flaring of the rails 20 and 22, the punch 28 is provided with longitudinally extending portions 36 and 36' which are received between the flanges 20 and 22, and laterally extending anvil portions 38 and 38' for flattening the flanges. The anvil portions 38 and 38' extend beyond the width of the strip 18. The portions of the punch 36, 38, 36' and 38' are connected by the curved portions 40 which act to impart the outwardly flared ends to the unflattened portions of the flanges 20 and 22. This outward flaring of the flanges on a curve is most important for a smooth running fastener.

As a result of the flattening operation, the strip 18 is made wider at the flattened area 30 than the original width of the flanged strip 18. Since, in the finished slider, the flattened area will be adjacent the neck or diamond portion, this added surface area presented to the fastener elements as they pass into and out of the slider is highly desirable.

The continuous strip 18 is then moved forward beneath a pair of laterally spaced notching punches. Only

one-punch, 42, is shown, but it will be understood that the two punches are mirror images, symmetrically arranged. The notching punches shear through both sides of the continuous strip within the flattened area 30, thereby removing material from the strip at the areas 44 and 46 and reducing the width of the strip at this point to the connecting neck portion 48. The notches 44 and 46 are substantially trapezoidal in shape, the short parallel sides each being on the inside of the strip. The notching is accomplished so that flattened portions 50, 50' and 52, 52' are left between the notches and the flared ends of the flanges in a direction lengthwise of the strip.

To provide means for receiving a pull, the strip is moved forward and subjected to lug forming and lug indenting operations to provide a lug of the type shown at 54 in Fig. 6. The main lug forming punch is shown at 56 in Fig. 5, and the two side indenting punches are shown at 58 and 58'. The latter produce indentations such as that shown at 59 in Fig. 6. These operations are well-known in the art and do not require further explanation. If a pin-lock, cam-lock, or automatic-lock slider is desired, a piercing tool may be provided at an additional station for forming a window or windows within the strip to permit passage of a pin, cams or detent into the slider channel of the finished slider. Here again the operation is well known in the art.

The strip is then moved forward again beneath a shearing punch 60 which completely severs the strip. The severance is at a line equivalent to the dot-dash lines 62—62 and 62'—62' when those portions of the strip are brought respectively beneath the punch. It will be observed that the cut 62—62 is midway between the flared ends 32, 32' and 34, 34' so that the resultant blank comprises two wings 64 and 66 which are equal in length and connected by a neck portion 48. Each wing has a pair of flanges, all of which are equal in length, and in parallelism throughout their lengths except at the ends which are in proximity to the neck portion 48, where they are flared outwardly.

In the final operation, the severed blank is moved over a die 68 where, in conjunction with a punch 70, the blank is bent at the neck portion 48 to bring the wings 64 and 66 into spaced, parallel relationship. The die and punch 68, 70, also act to indent the neck portion to thereby strengthen and rigidify this area. The finished slider body is shown in Fig. 6 where it is ready to receive the operating pull for completion into a slider.

It is believed that the advantages of my novel method of manufacturing sliders will be apparent from the foregoing detailed description. By pre-forming continuous and parallel flanges along the longitudinal edges of the continuous strip, a uniform and complete fill-in of metal at the flange areas is obtained, thereby resulting in a very strong cross-section of the material. The achievement of full fill-in, and thus more metal at the area where the flanges meet the flat portions of the wings, affords a cross-sectional strength which cannot be obtained by a bending or punch coining operation. In the final bending and neck forming operation, this strong and uniform cross-section of the material prevents collapse of the flanges at the areas where in the common form of slider the cross-section changes from the stem portion to the diverging portion. Also, unlike slider flanges formed by bending or coining in a reciprocating press, variations in pitch in the strip due to the variation in thickness and temper of the slider stock are obviated. The rolling of the continuous flanges into the strip as described, furnishes a very smooth contour to the slider stock thereby resulting in smooth running action of the finished slider. The rolling of the continuous flanges along the entire length of the strip is an inexpensive operation and is easily achieved.

When the segments of the continuous flanges are flattened and flared, not only are the flanges provided with a suitable curvature to facilitate the entry and emergence of the fastener elements into the channel of the slider,

but the slider is widened between the flared ends of the flanges and the neck portion to provide desired additional surface area for the fastener elements which pass into or out of the slider. It will also be apparent that the amount of material used in the fabrication of the product is kept to an absolute minimum. Also, since the only scrap is that resulting when the strip is notched, the amount of waste is exceedingly small. The power requirements for operating the rolls, the flattening and flaring punch, and the notching punch, are small.

It will be apparent that while I have shown and described my invention in several preferred forms, changes may be made in the procedures described without departing from the scope of the invention, as sought to be defined in the following claims.

I claim:

1. In the manufacture of sliders for slide fasteners from a continuous strip having continuous, parallel flanges along the longitudinal edges thereof, the distance between said flanges being equal to the width of the closing end of the slider channel in the finished slider, the method which includes forming flat areas by eliminating said flanges at spaced intervals, severing the thus formed strip across the flanges into blanks, and bending each of said blanks intermediate its ends at the flat portion to form a pair of spaced, parallel wings each provided with in-turned flanges.

2. A method as set forth in claim 1, wherein the continuous strip is formed by rolling.

3. In the manufacture of sliders for slide fasteners from a continuous strip having continuous, parallel flanges along the longitudinal edges thereof, the distance between said flanges being equal to the width of the closing end of the slider channel in the finished slider, the method which includes forming flat areas by eliminating said flanges at spaced intervals, forming a neck portion of reduced width within each flat portion of the strip, severing the thus formed strip into blanks, and bending each of said blanks intermediate its ends at the neck portion to form a pair of spaced, parallel wings each provided with in-turned flanges.

4. A method as set forth in claim 3, wherein the continuous strip is formed by rolling, and the neck portion of reduced width is formed by notching.

5. In the manufacture of sliders for slide fasteners from a continuous strip having continuous, parallel flanges along the longitudinal edges thereof, the distance between said flanges being equal to the width of the closing end of the slider channel in the finished slider, the method which includes forming flat areas by eliminating said flanges at spaced intervals, flaring the ends of the remaining flange portions adjacent the flat portions, severing the thus formed strip across the flanges into blanks, and bending each of said blanks intermediate its ends at the flat portion to form a pair of spaced, parallel wings each provided with parallel in-turned flanges, said flanges being flared at their top ends.

6. A method as set forth in claim 5, wherein the elimination of the flanges at spaced intervals and the flaring of the ends of the remaining flange portions is accomplished by flattening and flaring simultaneously.

7. In the manufacture of sliders for slide fasteners from a continuous strip having continuous, parallel flanges along the longitudinal edges thereof, the distance between said flanges being equal to the width of the closing end of the slider channel in the finished slider, the method which includes forming flat areas by eliminating said flanges at spaced intervals, flaring the ends of the remaining flange portions adjacent the flat portions, forming a neck portion of reduced width within each flat portion of the strip, severing the thus formed strip across the flanges into blanks and bending each of said blanks intermediate its ends at the neck portion to form a pair of spaced, parallel wings each provided with parallel in-turned flanges, said flanges being flared at their top ends.

8. A method as set forth in claim 7, wherein the continuous strip is formed by rolling, the elimination of the flanges at spaced intervals and the flaring of the ends of the remaining flange portions is accomplished by flattening and flaring simultaneously, the reduced width of the neck portion is formed by notching, and the bending of the blanks intermediate its end is accompanied by indenting.
